CLAIM

I claim the ornamental design for an art drying rack, as shown and described.

DESCRIPTION

FIG. 1 shows a perspective view of the art drying rack in the first embodiment with two vertical levels of shelves;

FIG. 2 shows a front elevational view of the art drying rack in the first embodiment;

FIG. 3 shows a back elevational view of the art drying rack in the first embodiment;

FIG. 4 shows a right elevational view of the art drying rack in the first embodiment;

FIG. 5 shows a left elevational view of the art drying rack in the first embodiment;

FIG. 6 shows a top plan view of the art drying rack in the first embodiment;

FIG. 7 shows a bottom plan view of the art drying rack in the first embodiment;

FIG. 8 shows a perspective view of the art drying rack in a second embodiment with four vertical levels of shelves;

FIG. 9 shows a front elevational view of the art drying rack in the second embodiment;

FIG. 10 shows a back elevational view of the art drying rack in the second embodiment;

FIG. 11 shows a right elevational view of the art drying rack in the second embodiment;

FIG. 12 shows a left elevational view of the art drying rack in the second embodiment;

FIG. 13 shows a top plan view of the art drying rack in the second embodiment; and,

FIG. 14 shows a bottom plan view of the art drying rack in the second embodiment.

That which is represented by broken lines illustrates environmental subject matter only and does not form part of the claimed invention.
